MOLDED ONE PIECE BINGO GAME BOARD

Dwight C. Brown, 5712 N. 20th St.,
Arlington, Va. 22205

Filed Feb. 7, 1975, Ser. No. 547,785

Term of patent 14 years

Int. Cl. D21—01
U.S. Cl. D34—5 SS

FIG. 3

FIG. 1

FIG. 2

FIG. 4

FIG. 5

FIG. 6

FIG. 7

FIG. 1 is a top plan view of a molded one piece Bingo game board showing my new design.

FIG. 2 is a bottom plan view of the game board shown in FIG. 1.

FIG. 3 is a cross section view of the typical nesting support post.

FIG. 4 is a cross section view of the typical flexible play control, in a ready-for-play "Up" position.

FIG. 5 is a cross section view of the typical flexible play control in the activated pressed "Down" position.

FIG. 6 is a fragmentary perspective view of the typical flexible play control when in the raised ready-for-play "Up" position of FIG. 4.

FIG. 7 is a fragmentary perspective view of the typical

flexible play control in the activated pressed "Down" position of FIG. 5.

I claim:

The ornamental design for a molded one piece Bingo game board, as shown and described.
